UNITED STATES PATENT OFFICE.

HENRY S. CREDLEBAUGH, OF NEW CARLISLE, OHIO.

LUGGAGE-CARRIER FOR BICYCLES.

SPECIFICATION forming part of Letters Patent No. 398,945, dated March 5, 1889.

Application filed September 1, 1888. Serial No. 284,377. (No model.)

To all whom it may concern:

Be it known that I, HENRY S. CREDLEBAUGH, residing at New Carlisle, in the county of Clark and State of Ohio, have invented certain new and useful Improvements in Luggage-Carriers for Bicycles, of which the following is a specification.

My invention relates to luggage-carriers for bicycles, and has for its object to provide a carrier which may be quickly attached or detached to the head of the bicycle, and which, when detached, will form a convenient hand-carrier; and it consists in forming the carrier out of a stout spring-wire body, which may be sprung in place upon the head and handle-bars at its rear end and suitably braced and supported at its forward end by a depending portion supported upon the brake-spoon or the lower portion of the head; and it further consists in the novel construction and combination of parts, as will be hereinafter fully specified, and particularly pointed out in the claims, reference being had to the accompanying drawings, in which—

Figure 1 is a perspective view of the improvement, showing the same applied to the head of a "vertical-fork" bicycle. Fig. 2 is a similar view of the improvement, showing the same in use as a hand-carrier. Fig. 3 is a plan view of the carrier, and Fig. 4 shows the carrier as applied to a "Star-bicycle" head.

In the accompanying drawings, A indicates the main or body portion of the carrier, and B the swinging bracket or handle portion, which are constructed out of stout spring-wire.

The body portion A consists of the side arms, a a, and the cross-bar a', said arms and cross-bar being formed of a single piece of wire, as shown. The outer ends of the arms a are formed with eyes a², in which is supported the cross-bar b of the bracket portion B, which is also formed of a single piece of wire, and which is composed of the cross-bar b, above referred to, and the side arms b' b', the outer ends, b² b³, of which are turned in toward each other and support the handle-block C. To arrange for the ready attaching or detaching of the carrier to the bicycle-head, and avoid the use of securing-straps, I form the cross-bar a' with downwardly and

inwardly bent lugs 1 1, arranged at the ends thereof, and with an inwardly-bent loop, 2, formed centrally of said bar.

D D denote the bundle-holding straps, which 55 may be secured to the cross-bar b of the bracket B, as shown in the drawings, or they may be detachable from said carrier, if desired. A transverse notch or groove, c, is formed in the handle-block G, the purpose of which will 60 be presently explained.

In applying the carrier to the bicycle the lugs 1 are placed over the handle-bars E, (see Fig. 1,) and the central loop, 2, is sprung over the securing-nut F, arranged at the upper 65 end of the head G. The depending portion or bracket B is then bent down, and the handle-block is turned so as to permit the notch c to be received upon the flat arm H of the brake-spoon, the notch in the handle-block 70 preventing the carrier from having any lateral movement, and thereby holding the same in a steady condition.

In applying the carrier to what is known as a "star" bicycle the lugs 1 at the ends are bent 75 downwardly and outwardly, as shown at 4 4, and the same fit over the handle-bars from the front side, instead of from the rear, as shown in Fig. 1, the central loop, 5, being slipped over the front of the nut F, as shown in Fig. 4. To 80 support the depending portion B, a suitable stop or clamp, S, is fastened on the head-bar T, and upon which the handle-block rests.

While I have shown and described my carrier as in use upon the vertical fork and the 85 "star machines," it is manifest that the construction of the carrier may be so modified as to adapt the same to various makes of bicycles without departing from the broad principle of my invention.

From the foregoing description, taken in connection with the drawings, the operation and advantages of my invention will be readily understood.

Having thus described my invention, what 95 I claim, and desire to secure by Letters Patent, is—

1. A luggage-carrier for bicycles, consisting of a body portion, A, formed of spring-wire having one end constructed to fit upon and 100 clamp the head or the handle-bars of the bicycle, and its opposite end provided with a

depending portion adapted to be supported at its lower end upon the bicycle-head, substantially as and for the purposes specified.

2. A luggage-carrier for bicycles, consisting 5 of a body portion, A, one end thereof constructed to fit upon and clamp the head or the handle-bars of the bicycle, and a depending portion or bracket, B, hinged at one end to the body portion, its opposite end adapted to 10 be supported upon the bicycle-head when in place, said portion B forming a handle portion when the carrier is detached from the bicycle, substantially as shown and described.

3. In a luggage-carrier, the combination, 15 with the body portion A, formed of spring-wire, having one end, a', constructed to fit upon and clamp the head and handle-bars of the bicycle, of the bracket portion B, formed of spring-wire, its upper portion, b, hinged in 20 the outer ends of the arms a a, its arms b' b' extended inward, forming supports for a handle-block, C, said block provided with a notch, c, substantially as and for the purposes described.

25 4. A luggage-carrier formed of spring-wire, consisting of the body portion A, said body portion formed of side arms, a, and cross-bar a', said cross-bar bent to form downwardly

depending lugs 1 and an inwardly-bent portion, 2, whereby said cross-bar may be clamped 30 upon the head and handle-bars of the machine, and a swinging bracket portion, B, hinged in the outer end of the arms, said portion provided with extended arms b b', and a handle-block, C, supported between said arms, 35 substantially as and for the purpose described.

5. As a new article of manufacture, a luggage-carrier for bicycles, formed of spring-wire, consisting of a body portion, A, having side arms, a, and a cross-bar, a', said cross-bar provided with clamping-lugs 1 1 and 2, whereby said cross-bar may be clamped to the head and handle-bars of a bicycle, the forward ends of the arms a being provided with eyes a², a swinging portion, B, consisting of 40 the cross-bar b, hinged in said eyes, said bar b bent to form arms b' b', said arms bent toward each other, as at b², said bent portions b² supporting a handle-block, C, said handle-block having a transverse notch, substantially 45 50 as and for the purpose described.

HENRY S. CREDLEBAUGH.
